UNITED STATES PATENT OFFICE.

ALFRED E. TOOMEY, OF EDMORE, NORTH DAKOTA.

GREASE-CUP.

1,160,014.

Specification of Letters Patent. Patented Nov. 9, 1915.

Application filed May 22, 1915. Serial No. 29,778.

To all whom it may concern:

Be it known that I, ALFRED E. TOOMEY, a citizen of the United States, and a resident of Edmore, in the county of Ramsey and 5 State of North Dakota, have invented a certain new and useful Improvement in Grease-Cups, of which the following is a specification.

This invention relates to an improvement 10 in grease cups.

One of the principal objects of the invention is to provide an improved grease cup having a cap hingedly connected to the body of the cup and carrying the plunger 15 and associated mechanism, whereby the cup may be readily opened for filling, by simply swinging the cap back upon its hinges and without the necessity of the removal of any of the parts.

20 Another object of the invention is to provide an improved grease cup having a cap or top to which a screw driven plunger is connected for reciprocation within the body of the cup, means being hingedly connected 25 to the cup for preventing the rotation of the plunger with the screw.

A still further object of the invention is to provide an improved grease cup of the 30 class described, which will be extremely simple, durable, efficient in operation, and inexpensive to manufacture.

With these and other objects in view which will become apparent as the description proceeds, the invention resides in the 35 construction, combination, and arrangement of parts hereinafter more fully described and claimed and illustrated in the accompanying drawings in which like characters of reference indicate like parts throughout 40 the several figures, of which—

Figure 1 represents a view in section taken vertically and centrally through a grease cup constructed according to my invention. Fig. 2 represents a view in section taken horizontally on the plane indicated by the line 2—2 of Fig. 1, looking in the direction indicated by the arrow. Fig. 45 3 represents a top plan view of the cup.

In carrying out my invention, I provide 50 a cup whose body is indicated at 5. The body as shown, is substantially cylindrical and is provided with an inclined floor 6 merging centrally into an exteriorly screw threaded hollow stem 7 adapted to be connected with the part to be lubricated where-

by to dispose the grease cup in proper position.

A dome-shaped cap or cover 8 is hingedly connected as at 9 with the body 5. The upper edge of this body is beveled inwardly 60 and the lower edge of the cap 8 is correspondingly beveled whereby as clearly indicated in Fig. 1, when the cap is in closed position upon the body an extremely tight joint between the edges of the body and cap 65 is provided as indicated at 10. At a point diametrically opposed to the point at which hinge 9 is connected with cap 8, a resilient catch or arm 11 is connected to said cap, the lower end of which depends below the 70 lower edge of the cap. A pin 12 carried upon the body 5 is adapted to be engaged by the arm 11 through an opening in the latter, whereby to maintain the cap in closed position upon the body portion at will. 75

Disposed within cap 8 and swiveled near its upper end at the apex of the cap, is a threaded bolt or screw 13. The latter extends within the cap and when said cap is in closed position upon the body of the 80 grease cup, lies in the axis of the latter. Secured in suitable manner to the upper end of screw 13 on the outside of cap 8, is a turn button 14. The edges of the latter are corrugated or scalloped as at 15, while the 85 central portion 16 is of a concavo-convex formation whereby to snugly rest upon the outer surface of the cap. By actuating this turn button 14, the screw 13 may be turned in one direction or another at will. 90

The plunger, through the operation of which suitable pressure is adapted to be exerted upon the contents of the cup at will, includes the upper and lower plates 17, between which a leather or other suitable washer 18 is bound, the edges of said washer being stamped over to provide a packing for the plunger. This plunger is of a diameter substantially equal to or slightly less than the internal diameter of body 5. The 100 plunger is carried upon the lower end of a squared shank 19, having a threaded longitudinal bore through which the screw 13 is turned.

In order that the shank 19 may be held 105 against rotation with the screw 13 while the latter is turned in reciprocating the plunger within the grease cup, a substantially rectangular guide loop 20 is provided. This loop at one end is hingedly connected 110

through the medium of a clip 21, with the cap 8 inside of the latter, and at a distance above the lower edge of said cap. The loop 20 is adapted to swing upon its hinged 5 end upwardly and downwardly. The stem 19 extends through the loop as clearly indicated in Fig. 2, and the loop is of such length that no matter whether the stem or shank 19 be at the upper or lower extremity 10 of its movement, it will be embraced on two sides by the side bars of the loop. This guide loop rests at its outer end upon the plunger through the action of gravity. The length of the shank 19 is such that the plunger 15 may be forced clear into the lower end of the grease cup in order to entirely empty the same.

Such a grease cup as I have provided may readily be opened by simply disengaging the 20 arm 11 from pin 12 and swinging the cap back upon its hinge 9, so that no disadvantages incident to the ordinary grease cup, through the operation of removing various parts of the cup, are experienced. Before 25 swinging the cap into open position, the plunger will be withdrawn into the cap so as to be in position when the cup is filled with grease, to be moved into the upper end of the cup whereby to exert the desired pressure 30 upon the contents thereof. All of the operative parts of the device are carried by the cap, so that an extremely compact and simple construction and arrangement of parts is thus provided.

15 Although I have described the preferred embodiment of my invention, I may desire to make such changes in the construction, combination, and arrangement of parts thereof, as do not depart from the spirit of 20 the invention and the scope of the appended claims.

I claim:—

1. A grease-cup comprising a cylindrical body, a dome-shaped cap hingedly connected therewith, means for detachably connecting the cap and body together in closed 5

position, a screw swivelly connected with the cap and disposed within the same, a turn button fixedly connected with the screw and arranged exteriorly of the cap, a squared shank 50 through which said screw is threaded, a plunger carried by the shank, and a rectangular loop hingedly connected adjacent one end with the cap and through which loop said shank extends, said loop adapted 55 to maintain the shank against rotation.

2. A grease cup comprising a cylindrical body, a dome-shaped cap hingedly connected therewith, a screw swivelly connected with the cap and extending within the same, means whereby the screw may be operated at will from without the cap, a shank 60 threaded upon the screw and being provided with a plunger, and means hingedly connected with the cap within the latter and 65 engaging the shank for preventing rotation of the latter.

3. A grease-cup comprising a body, a cap hingedly connected therewith, a plunger connected with the cap and adapted to be 70 reciprocated at will within the body, and means carried by the cap for preventing rotation of the plunger under influence of its operating means.

4. A grease-cup including a body, a cap 75 hingedly connected therewith, a screw carried by the cap and adapted to be rotated at will, a plunger mounted upon the screw, and means carried by the cap for preventing rotation of the plunger when the screw is 80 turned.

5. In a grease cup, a body, a cap hingedly connected therewith, a plunger mechanism carried by the cap, and a loop hingedly connected to the cap and operably engaging the 85 plunger mechanism for limiting the latter to a reciprocating movement.

ALFRED E. TOOMEY.
